ABSTRACT

A device for blocking the movement of a movable crane on an overhead trackway when it comes to the end of the trackway includes a mechanism mounted at the end of the trackway and supporting a buffer arm having a buffer end portion thereon which is alignable with the trackway over which a crane is movable in order to block the movement of the crane toward the end of the trackway. The arrangement includes a motor drive for pivoting the buffer arm about an axis which is substantially parallel to the longitudinal axis of the trackway for the purpose of shifting the buffer arm from a position at which it blocks the moving crane to one at which it is removed from a blocking position to permit traveling movement of the crane from one trackway to another trackway which is aligned therewith. The adjacent trackway is adapted to have a similar buffer construction with a pivot lever element which is exposed when the two trackways are aligned in a position such that actuation of one buffer arm to move it out of a blocking position will be effective to move the other buffer arm of the adjacent trackway out of a blocking position.

BLOCKING MECHANISM FOR AN OVERHEAD CRANE TRACKWAY

SUMMARY OF THE INVENTION

This invention relates in general to the construction of overhead crane devices, and in particular, to a new and useful blocking device which includes a pivotal arm member carrying a buffer and which is adapted to be located at an end position on a trackway and which is movable between a position in which it blocks the movement of a crane off the end of the trackway to one which permits the movement of the crane for example, on to another trackway which is aligned with the first.

The present invention is particularly applicable to a device for controlling the movement of a crane along a crane trackway in order to prevent the crane from dropping off the end. Such a blocking device is applicable to all lifting devices such as trolleys, hoists, stacking cranes, etc., which travel on tracks which are moved transversely themselves. The known blocking devices for preventing the movement off the end of the trackway when it is not aligned with another trackway includes a pivoting arm device in which the arm is pivotable about an axis disposed perpendicular to the crane track. The arm blocks the crane track in the lowered condition and it frees it in its raised condition. Raising of the pivot arms is accomplished by a linkage which is actuated when two adjacent trackways are locked together. After unlocking the trackways, the pivoting arms are supposed to drop due to their own weight or due to a spring force. The pivoting devices do not function perfectly when the friction in the bearings of the transmission linkage becomes too great, or when the blocking device or parts thereof are bent due to an overstressing. Preferably the blocking devices are equipped with buffers to absorb the impact shocks. However, the buffers must not project into the path of travel by the movable crane or trolley. Therefore, the blocking device protrudes far beyond the buffer and stresses it and the bearing of the blocking device through a lever arm which further increases the stress. Weak forces only can be transmitted by the known blocking devices and for this reason they are suited for light crane trackways only.

In accordance with the invention, a pivotable blocking device for heavy duty crane tracks or trackways is provided which is capable of operation without impairment and which is not subject to extraordinary bearing friction or friction which is produced by deformed components. The construction includes a buffer arm which is pivotable about an axis which is substantially parallel to the trackway axis and which is moved by a motor which is connected thereto such as by a driving sprocket and shaft connection. The motor is arranged to rotate in two directions of rotation and thus can pivot the buffer both into a free position and into a blocked position. The buffer element is attached to the pivoting arm which is mounted in a pivot housing attached to the crane trackway. The bearing points for the pivot housing may be spaced relatively far apart and the pivot arms are only so long that they can be swung with the buffer out of the range of the suspended crane or the trolley. Because of this compact design no great forces will affect the bearing points when the crane impacts on the buffer.

According to another feature of the invention, the pivoting arm is connected to the motor by a power transmission which may be, for example, a drive shaft having a sprocket wheel and a chain engaging with the wheel and a wheel of the motor. The drive may also be similar power transmission such as gears or belts or the like. With the drive shaft described, however, the motor may be located outside of the range of the crane trackway so that it will not be block the movement of the crane.

Preferably, the buffer is carried on a rod member which is biased by spring means arranged in a cylinder housing and which provide a dampening action. The construction permits attenuation of the impact shocks and also reduces noise due to the appropriate material selection for the damping buffer.

In accordance with a further feature of the invention the pivot arm includes a pivot plate which is disposed to actuate a similar pivot plate of a buffering device of similar nature contained on the trackway which may be aligned with the first trackway. The pivot plate of the first trackway is disposed horizontal to the shaft direction of the pivoting arm but is staggered in respect to height as to the adjacent pivot plate of the buffer mechanism of the next adjacent trackway. The pivotal motion of the first buffer arm is transmitted to the second buffer arm when the two trackways are aligned. The horizontal staggering of the two pivot plates permits the movement of the trackways beyond the alignment position.

Accordingly, it is an object of the invention to provide an improved buffering mechanism for an overhead trackway for cranes, trolleys and the like, which includes a buffer arm member carried on the trackway adjacent an end thereof and which is shiftable about an axis substantially parallel to the trackway axis for the purpose of positioning the arm in a blocking position or in a free position in respect to the associated trackway.

A further object of the invention is to provide a device for preventing the movement of a traveling crane or trolley off the end of the trackway or trackways which may be shifted transversely and, for example, aligned with another trackway and which includes a pivotal arm member carrying a buffer on a first trackway which may be shifted between a blocking position aligned with the trackway or a position offset from the trackway and which includes lever means for actuating the adjacent buffer mechanism to do the same thing.

A further object of the invention is to provide a buffering mechanism for a trackway over which a crane or trolley is movable and which is simple in design, rugged in construction, and economical to manufacture.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which there is illustrated and described a preferred embodiment of the invention.

BRIEF DESCRIPTION OF THE DRAWINGS

In the drawings:

FIG. 1 is a partial side elevational view partly broken away showing two transversely aligned trackways over which a crane is movable and which includes a buffer mechanism constructed in accordance with the invention; and

FIG. 2 is a section taken on the line 2—2 of FIG. 1.

GENERAL DESCRIPTION OF THE PREFERRED EMBODIMENT

Referring to the drawings in particular, the invention embodied therein is employed in association with a suspension or overhead crane system generally designated 50 which includes one or more trackways 1, and 1' movable in respective transverse areas and capable of being aligned so that the axis of the trackways defined thereby may be aligned for movement of a crane or trolley 52 from one trackway onto the other. In the aligned or flush position of the two trackways 1 and 1' they are prevented by means of a holding device generally designated 13 from shifting laterally with respect to each other.

In accordance with the invention, the trackways 1 and 1' each have a buffering mechanism or device generally designated 54 and 54', respectively. Each buffering mechanism 54 and 54' includes a resilient buffer member 10 which is carried on the end of a rod member 56 and which is biased by springs 9 in a direction to project outwardly in the associated trackway toward the interior of the trackway and in the active position provides a buffer or stop for preventing further movement of the associated traveling crane or trolley 52. The springs 9 provide for the attenuation of the shock upon impact of the crane 52 against the buffer 10.

The cylinder 8 is attached to a pivoting arm 7 which is pivotally mounted in a pivot housing 6 for pivotal movement about an axis 11 which is substantially parallel to the axis of the trackway. The housing 6 is fastened to the end of the associated trackway 1 or 1' at a location in which the buffer 10 will be spaced inwardly from the adjacent end thereof.

In accordance with a feature of the invention a motor 2 is mounted in a non-blocking position over the trackway 1 and it is equipped with a sprocket wheel on 45

its driving shaft (not shown) which drives a sprocket chain 3 which is engaged with a sprocket wheel 4 of a drive shaft 5. The drive shaft 5 is connected through a universal joint 58 to a pivot member 60 for the arm 6.

5 Rotation of the motor 2 in a selected direction will pivot the arm 6 between a blocking position shown in solid lines to a dotted line position shown in FIG. 2 at which it is located to free the movement of the crane 52 and will be free of any blocking action in respect to the

10 crane moving along the trackway.

In accordance with a further feature of the invention a pivot plate 12 is attached to the member 11 and it rotates therewith during the movement of the arm 7. The plate 12 on the buffering mechanism 54 is offset

15 vertically from the corresponding plate 12 of the buffering mechanism 54' so that it will not interfere with the transverse movement of one track 1 in respect to the other track 1'. However, when the tracks are aligned, rotatable movement of the plate 12 on the buffering mechanism 54 will cause a corresponding rotatable movement of the plate 12 on the buffering mechanism 54'.

What is claimed is:

1. A blocking device for use with a transversely movable trackway over which a train or trolley is moved, comprising a buffer arm member, means mounting said buffer arm member adjacent the end of the trackway for pivotal movement between a blocking position blocking the end of the trackway and a free position freeing the end of the trackway, and motor means connected to said buffer arm member for shifting said buffer arm member between said blocking position and said free position, a first trackway carrying said buffer arm member, a second trackway carrying a second buffer arm member similar to said first member, said first buffer arm member and said second buffer arm member having actuating plates thereon which are rotatable therewith and which project outwardly from the end of the associated trackway, said first buffer arm member actuating plate being rotatable with said arm and engageable with the actuating plate of said second buffer arm member to rotate it, said plates being offset vertically in order to permit transverse movement of said trackways relative to each other.
